HENCHEL DAFFRON, OF DETROIT, MICHIGAN.

SPARK-PLUG.

1,295,126.

Specification of Letters Patent.

Patented Feb. 25, 1919.

Application filed June 1, 1918. Serial No. 237,729.

To all whom it may concern:

Be it known that I, HENCHEL DAFFRON, a citizen of the United States, residing at Detroit, in the county of Wayne and State 5 of Michigan, have invented certain new and useful Improvements in Spark-Plugs, of which the following is a specification.

This invention relates to internal combustion engines, and more especially to the 10 ignition thereof; and the object of the same is to produce an improved spark plug.

The invention consists first in a peculiar means for mounting the porcelain within the body of the plug, and second in the 15 peculiar formation of the lower end of the body so that the sparks may drive the carbon laterally out of such body.

Details are set forth in the following specification and claims, and reference is 20 made to the drawings, wherein:

Figure 1 is a central vertical section of this improved plug and

Fig. 2 is a bottom plan view thereof.

The body is indicated by the numeral 1, 25 internally shouldered as at 2 and externally flanged as at 3 about opposite the shoulder. The lower end of the body is provided with preferably four notches 4 disposed about as seen in Fig. 2 and one terminal 5 passes out 30 of said end between two of the notches and turns inward, while the other terminal 6 passes down through the center of the porcelain 7, its upper end 8 having suitable means for attachment of the wire from the 35 ignition system. The return of the current is through the terminal 5 and body 1, and through the flange 3 which is borne down into reliable contact with the cylinder by screwing the plug into an appropriate opening 40 therein, for which purpose it is threaded as shown at 19, the threads passing down for a considerable distance on the fingers between the several notches.

The porcelain 7 preferably is provided 45 with an exterior annular shoulder 17 which is larger than the body of the porcelain and yet of a size to pass into the bore of the body 1; and around the upper end of said porcelain a heading 18 is welded or otherwise 50 formed so as to protect the porcelain from injury by accidental blows. The upper end of the body 1 is internally threaded as at 11, and a packing nut 12 goes into the same around the porcelain, its lower end

bearing on the shoulder 17 and therefore 55 pressing the latter and the entire porcelain downward. Beneath said shoulder and above the shoulder 2 in the body are disposed a plurality of washers. The numeral 13 designates the upper washer which is 60 quite thin and of metal such as steel. The numeral 14 designates the intermediate washer which is preferably of fiber inclosed within copper and of that type known as a packing washer. The numeral 15 designates the lowermost washer which is preferably of steel, and it has around its inner edge a depending flange 16 which passes down through the bore within the shoulder 2 of the body as shown. With this construction, when the nut 12 is screwed down onto the shoulder 17 and the latter is borne down onto the upper washer 13, the packing washer 14 is more or less compressed between the two metal washers and the porcelain 75 is accurately centered within the body 1, while the escape of pressure upward past the plug is prevented, as well as short-circuiting. The employment of a plurality of notches 4 through the wall of the body 1 80 at its lower end and around the terminals 5 and 6, is what I consider an extremely important feature of my invention. At each upward stroke of the piston the charge is compressed in the head of the cylinder and 85 to an extent within the open lower end of the spark plug, and therefore when the spark occurs the compressed charge is exploded at the spark gap and the explosion itself scatters the flame in all directions. 90 Obviously it finds its most ready exit from the spark plug downward because there is no obstruction in that direction. Also it passes upward around the reduced lower end of the porcelain. But with my invention it 95 passes also outward radially in four directions provided there are four of the notches numbered 4, and therefore all parts of the compressed charge in the head of the cylinder around the spark plug are ignited simultaneously. Also the scattering of the explosion in this direction drives out of the lower end of the spark plug at each explosion, such particles of carbon as might otherwise accumulate therein, and therefore this simple 100 expedient makes the spark plug practically self-cleaning. I have found by a thorough test of a spark plug constructed as herein

described that the statements I make are corroborated by the facts.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

15 1. In a spark plug, the combination with a metal body having an internal shoulder and internal threads at its upper end; of a porcelain provided with a shoulder standing above that of the metal body, terminals 20 respectively carried by the body and the porcelain, a nut screwed into the upper end of the body, a flanged washer resting on the shoulder of the body, a packing washer above the flanged washer, and a flat washer

above the packing washer beneath the shoulder on the porcelain. 25

2. In a spark plug, the combination with a tubular body having an internal shoulder, internal threads at its upper end, and notches in its lower end; of a porcelain 30 whose body is smaller than the bore of said metal body and is provided with a shoulder fitting said bore and standing above that of the metal body, terminals respectively carried by the body and the porcelain, a nut 35 screwed into the upper end of the body, a flanged washer resting on the shoulder of the body, a packing washer above the flanged washer, and a flat washer above the packing washer beneath the shoulder on the porcelain. 40

In testimony whereof I affix my signature in presence of two witnesses.

HENCEL DAFFRON.
